(57) **CLAIM**

The ornamental design for a portion of a box, as shown and described.

DESCRIPTION

FIG. 1 is a front elevation view of portion of a box showing our new design;

FIG. 2 is a rear elevation view thereof;

FIG. 3 is a left-side elevation view thereof;

FIG. 4 is a right-side elevation view thereof;

FIG. 5 is a top plan view thereof; and,

FIG. 6 is a bottom plan view thereof.

The dashed broken line showing in the drawings are for illustrative purposes only and form no part of the claimed design. The dotted broken line showing in the drawings represent boundaries of the claimed design and form no part of the claimed design.
